UNITED STATES PATENT OFFICE.

WILLIS DODGE, OF BLAINE, MAINE.

CAR-COUPLING.

SPECIFICATION forming part of Letters Patent No. 466,160, dated December 29, 1891.

Application filed March 25, 1891. Serial No. 386,352. (No model.)

To all whom it may concern:

Be it known that I, WILLIS DODGE, of Blaine, in the county of Aroostook and State of Maine, have invented a new and Improved 5 Car-Coupler, of which the following is a full, clear, and exact description.

My invention relates to improvements in car-couplers, and more especially to certain attachments which may be applied to the ordinary link-and-pin coupler; and the object of my invention is to produce a simple and efficient device which may be easily applied to a common form of coupler, and which will permit cars to be automatically coupled without the necessity of a brakeman stepping between them.

To this end my invention consists in certain features of construction and combinations of parts, which will be hereinafter described and claimed.

Reference is to be had to the accompanying drawings, forming a part of this specification, in which similar figures of reference indicate corresponding parts in all the views.

Figure 1 is a broken side elevation of a car-coupler provided with attachments embodying my invention. Fig. 2 is a broken vertical longitudinal section of the same on the line 2 in Fig. 3. Fig. 3 is a front end view of the 25 coupler, partly in section, on the line 3 3 in Fig. 2. Fig. 4 is a detail sectional view showing a spring-plate in position to hold up a coupling-pin. Fig. 5 is a broken side elevation of the sliding bar and the lever mechanism thereon, showing the same in position for operating a lifter. Fig. 6 is a side elevation of the sliding bar with the lever mechanism in a raised position, and Fig. 7 is a broken detail view of a preferred way of securing the 30 spring to the sliding side bar.

The draw-head 10 is of the usual construction, having the ordinary recess 11 in the front end, which is adapted to receive a link 12, and the draw-head also has a vertical bore 45 extending through it to receive a coupling-pin 13, which engages the link 12 in the usual way.

In the upper part of the draw-head is a plate 14, the front end of which is doubled upward, as shown at 15, so as to project opposite the front end of the draw-head, and the plate is held to slide in a keeper 16, which

is secured in the upper portion of the draw-head. The plate 14 is normally pressed forward by a spring 18, which encircles the rear 55 end of the plate and is held in a recess 17, the front end of the spring pressing against a shoulder 16^a on the plate.

The coupler is provided with a swinging lifter 19, which is intended to automatically 60 lift the link when the cars are to be coupled, and the lifter has two members 20, which at their rear ends are pivoted to opposite sides of the draw-head, as shown at 21, and one of which is elongated, as shown at 22, so as to 65 project upward above the point at which it is pivoted. The members 20 extend forward beyond the front end of the coupler, and are bent, as shown at 23, so as to extend upward in front of the draw-head, and at their upper 70 ends they are united by a cross member 24, as best shown in Fig. 3, which cross member is slightly concaved, so that it will prevent a link from slipping from it. The length of the vertical portions 23 of the lifter is such that 75 when the lifter is raised the cross member 24 will come opposite the mouth of the coupler, and the lifter is ordinarily held downward, as shown in Fig. 1, by a spring 25, which is secured to the draw-head in the rear of the 80 lifter, and which presses forward upon the elongated end 22 of the lifter.

A bar 26 is held to slide upon one side of the draw-head 10 above the lifter 19, the bar moving longitudinally in keepers 27, and the 85 front end of the bar is formed into a shank 28, which shank extends forward through a recess in one side of the draw-head and terminates in a button 29, and the bar is normally pressed forward, so that the button 29 will be 90 well in advance of the draw-head, by means of a spiral spring 30, which is coiled around the shank between the button and the forward keeper 27. Instead of having the spring secured to the bar in this way, however, I prefer to provide the bar with a projecting lip 26^a on the upper side and to secure one end of a spring 30^a to this lip and the opposite end to a lug 10^a on the rear portion of the draw-head, as in Fig. 7, and the tension of 100 the spring will normally throw the bar forward. An arm 31 is pivoted on the inside of the sliding bar 26, the arm being pivoted at its rear end, as shown at 32, and the arm is

normally held upward, as shown in Fig. 4, by means of a spring 33, which is secured to the rear end of the bar 26, and which presses upon the rear upper portion of the arm 31.

5 The free end of the arm 31 is provided on the under side with a rearwardly-inclined cam 34, which is adapted to project beneath the lower edge of the bar 26, and above the cam is a recess 35, in which is pivoted one end of 10 a link 36, and the link extends upward and is pivoted at its upper end to a sliding bar 37, which is held in suitable keepers, and which is recessed, as shown at 37^a, so that the end of the link may fit closely and still be 15 permitted to move. The front end of the bar 37 is adapted to project beyond the front end of the square portion of the sliding bar 26 and to contact with a shoulder 38 near the front end of the draw-head, as best shown in 20 Fig. 1.

The operation of the coupler is as follows: When two cars come together, the draw-head of one coupler will strike the button 29 of the other, as indicated by dotted lines in Fig. 1, 25 and this will push rearward the sliding bar 26, and the cam 34, acting on the elongated end 22 of the lifter 19, will cause the front end of the lifter to swing upward, so as to lift the link 12 and guide it into the draw-head, and 30 before the two draw-heads come together the bar 26 will have moved backward far enough so that the bar 37 cannot contact with the shoulder 38 of the draw-head and the spring 33 will raise the arm 31 and the cam 34, as 35 shown in Fig. 4, thus permitting the lifter to drop, so that its forward end cannot be nipped between the draw-heads. As the draw-heads continue to advance toward each other one draw-head will strike the bent end 15 of the 40 plate 14, thus pushing the plate inward until the recess in the plate comes beneath the coupling-pin 13, and the pin will then drop through the plate and through the link 12, as shown in Fig. 2. When cars are to be uncoupled, 45 the pin 13 is removed and the plate 14 springs forward, and when the draw-heads are not in contact the bar 26 is pushed forward by the spring 30, so that the front end of the bar 37 will contact with the shoulder 38 on the draw-

head, and this causes the link 36 to assume 50 nearly a vertical position and to push the free end of the arm 31 downward, so that the cam 34 will be in position to operate the lifter.

Having thus described my invention, I claim as new and desire to secure by Letters 55 Patent—

1. In a car-coupler, the combination, with a draw-head having a spring-pressed plate therein, said plate having a projecting forward end and a recess to receive a pin, of a 60 swinging lifter pivoted to the draw-head and adapted to extend in front of the same, a sliding bar mounted on the draw-head and extending in front of the same, and a lever mechanism mounted on the bar and adapted to operate the lifter, substantially as described.

2. In a car-coupler of the character described, the combination, with a draw-head and a swinging lifter having an elongated end, of a sliding bar mounted on the draw- 70 head above the lifter and arranged to project in front of the draw-head, an arm pivoted on the bar and having a depending cam to engage the end of the lifter, a sliding bar pivoted on the main bar and adapted to engage a shoulder 75 on the draw-head, and a link connecting the smaller of the sliding bars and the arm, substantially as described.

3. In a car-coupler of the character described, the combination, with a draw-head, 80 of a lifter pivoted to opposite sides of the draw-head and having a bent end adapted to swing in front of the same and having its rear end elongated, a spring-pressed main bar slidably mounted on the draw-head above the 85 lifter and arranged to project in front of the draw-head, a spring-pressed arm pivoted on the main bar and adapted to engage the elongated end of the lifter, a sliding bar mounted on the main bar and adapted to engage a 90 shoulder on the draw-head, and a link connecting the sliding bar and the cam-arm, substantially as described.

WILLIS DODGE.
